UNITED STATES PATENT OFFICE.

BERKET H. TAYLOR, OF ALCOLU, SOUTH CAROLINA.

IGNITION-SWITCH LOCK.

Application filed August 3, 1925. Serial No. 47,801.

The purpose of the invention is to provide a device involving the principles of a permutation lock for use in connection with the ignition switches of auto vehicles, so that for the actuation of the switch, it shall be necessary for the operator to know the combination; to provide a construction of this sort in which the combination may be varied, in the event that a previous combination shall have become known; and to provide a device of this sort which is extremely simple in construction and may, therefore, be manufactured cheaply and marketed at small cost.

With this purpose in view, the invention consists in a construction and combination of parts of which a preferred embodiment is illustrated in the accompanying drawings, wherein:

Figure 1 is a front elevational view of a portion of an instrument-board with the position of the switch indicated thereon.

Figure 2 is a central diametrical sectional view through the switch detached.

Figure 3 is an edge elevational view, the instrument-board being shown in section.

Figure 4 is a horizontal sectional view on the plane indicated by the line 4—4 of Figure 2.

Figure 5 is a bottom plan view on a reduced scale of the switch detached.

Figure 6 is a top plan view of the bottom of the switch casing.

Figure 7 is a sectional view on the plane indicated by the line 7—7 of Figure 4.

The disks 10, 11 and 12, which constitute the movable elements of the device, are disposed in superposed relation concentrically with the shaft 14 which passes through central eyes formed in the disks, the disks being spaced apart by interposed collars 15 and the uppermost disk being actuatable by a knurled knob 16 secured to a thimble 17 flanged, as at 18, the flange 18 being secured to the uppermost disk 10. The knob 16 is also connected to the shaft or spindle 14, a pin 19 passing diametrically through a depending flange on the knob, through the sleeve and through the shaft.

The several disks 10, 11 and 12 are of pan-shape with their upstanding flanges 20 concentrically arranged, so that their peripheral flanges 21 may lie in a common plane. The top face of each peripheral flange is inscribed with the numbers 1 to 8, inclusive, preferably of luminous material, the digits being uniformly spaced angularly, so that

in the rotation of the disks, the desired digit may be brought to view under the observation opening 22 in the instrument-board 23, this opening being covered by a transparent panel 24.

The several disks are housed in the casing of which the front wall consists of the instrument-board 23. The casing comprises a ring member 24 made preferably of flat steel and secured to the instrument-board and flanged at its opposite edge, as indicated at 25, the flange at uniformly spaced points being provided with key-hole slots 26. The bottom or back 27 of the casing carries the integral peripheral ears 28 spaced according to the spacing of the slots 26 and the bottom may be passed into the casing, the ears passing through the open sides of the slots 26, thereafter a slight angular or rotary movement imparted to the bottom will result in the movement of the ears 28 onto the flange 25 and the passage of pins 29 into the lateral extensions of the slots 26, the pins 29 being carried by the ears 28 and disposed at right angles to the plane of the bottom 27.

The ignition switch, which comprises the angularly movable or rotary member 30, is housed in a supplemental casing 31 having a removable bottom 32, the casing 31 being identical with the casing or housing of the disks but on a smaller scale and the removable bottom 32 carrying the fixed contact 33 designed for cooperative action with the movable contact or switch member 30. The lighting switch 34, while smaller, is identical in construction with the ignition switch and is carried in a supplemental casing 35 identical with the casings or housings of the ignition switch and the disks. The supplemental casing 35, while carried by the removable bottom 27, is disposed to one side of the housing or casing of the disks, so that the lighting switch may be actuated independently of the ignition switch and the locking means therefor.

The bottom 27 is provided with a central opening 36 and carries a flat spring 37 covering said opening and bearing upon the inner or rear end of the shaft 14 when the bottom is attached. This spring serves to retain the bottom in position by interposing frictional resistance to the angular movement with the possibility of inadvertent disengagement of the bottom. To preclude axial or longitudinal movement of the shaft 14, the thimble 17 is surrounded by a collar

38 interposed between the flange 18 and the inner face of the instrument-board, and the spring 37 bearing upon the end of the shaft interposes frictional resistance sufficient to prevent its too free turning.

The disks 10, 11 and 12 are each provided with threaded openings or eyes 39 angularly spaced according to the spacing of the digits on their peripheral flanges but these eyes are 10 all at uniform radial distances from the shaft so that, in certain positions of the various disks, the eyes are in registration, and normally all those eyes except those desired for use are plugged, as by screws 40. The 15 plan for plugging all but one or for plugging several in each disk leaves at least one open in each disk so that the several disks may be arranged with the eyes 39 in alignment with the bushing 41 in the face of the 20 instrument-board. In such position of the several disks, the switch operating key 42 may be inserted, the shank 43 of the latter passing through the bushing 41, through the 25 several eyes 39 and entering the movable member 30 of the ignition switch, so that member may be actuated and the ignition circuit closed.

In the actuation of the lock, the upper or outer disk 10 is the only member actuated by 30 the knob 16. When the number which has been selected for use to define the open or unlatching position of this disk has been selected, that number is brought under the observation opening 22 and the hole or eye 35 39 diametrically opposite will then be in position under or behind the bushing 41. This opening must be left open and all of the other openings or eyes 39 are preferably plugged by the insertion of the screws 40. 40 The same method of setting applies to the remaining disks, so that when the selected three numbers are below the observation opening, there will be three unobstructed openings 39 below or behind the bushing 41, 45 so that the actuating switch key may be inserted. When the disks have been moved so that these selected openings or eyes 39 have been disaligned, realignment may be effected by the actuation of the knob 16.

50 The rotation of the knob 16 imparts rotary movement to the upper or outermost disk 10 and this motion is finally communicated to the disk 11 when the radial pin 44 on the upstanding flange of the disk 10 55 engages an inwardly directed pin 45 on the corresponding flange of the disk 11. The two disks then rotate together until the pin 46 on the outside of the upstanding disk 12 engages an inwardly directed pin 47 on the flange of the disk 12. The three disks are then rotated by the knob until the 60 first digit of the combination, as 4 in Figure 1, appears under the observation opening. Reverse movement must then be im- 65 perted to the knob 16, for further movement

in the same direction would result in carrying the disk 12 around with the knob but to leave the digit 4 under the opening, the operative connection between the disks 11 and 12 must be disengaged and the reverse 70 movement of the knob will effect this since the pin 44 will then move away from the pin 45 and when the disk 10 has completed a movement of 360 degrees, the pin 44 will engage the pin 45 on the other side and 75 rotate the disk 11 in the opposite direction and, when the necessary digit such as 6 in Figure 1 appears below the observation opening, the rotation of the knob is reversed and the disk 12 moved in the original direction until its selected digit, such as 3 appearing in Figure 1, falls below the observation opening. The unobstructed openings or eyes are then aligned and the switch key may then be inserted and the switch actuated. 85

In the relocking operation, the mere rotation of the knob, after the withdrawal of the switch actuating key, will serve to effect the necessary disarrangement of the relation between the disks, so that they will obstruct 90 the passage of the switch-actuating key.

The invention having been described, what is claimed as new and useful is:

1. A switch lock of the kind indicated comprising a plurality of concentric disks 95 of pan shape and arranged in superposed relation and provided with peripheral flanges lying in a common plane and inscribed with indicating characters, manual means for actuating one of the disks, and operative connections between it and the other disks.

2. A switch lock of the kind indicated comprising a plurality of concentric disks of pan shape and arranged in superposed 105 relation and provided with peripheral flanges lying in a common plane and inscribed with indicating characters, manual means for actuating one of the disks, and operative connections between it and the other disks, said operative connections comprising abutment pins disposed radially of the upstanding flanges of the disks.

3. A switch lock of the kind indicated comprising a plurality of concentric disks 115 of pan shape and arranged in superposed relation and provided with peripheral flanges lying in a common plane and inscribed with indicating characters, a knob connected with the uppermost disk, and 120 radially disposed abutment pins arranged on the upstanding flanges of the disks.

4. A switch lock of the kind indicated comprising a plurality of concentric disks of pan shape and arranged in superposed 125 relation and provided with peripheral flanges lying in a common plane and inscribed with indicating characters, a knob connected with the uppermost disk, and 130 radially disposed abutment pins arranged

- on the upstanding flanges of the disks, the disks being provided with axially aligned circular series of perforations aligning with the alignment of the indicating characters.
- 5 5. A switch lock of the kind indicated comprising a plurality of concentric disks of pan shape and arranged in superposed relation and provided with peripheral flanges lying in a common plane and inscribed with indicating characters, a knob 10 connected with the uppermost disk, radially disposed abutment pins arranged on the upstanding flanges of the disks, the disks being provided with axially aligned circular 15 series of perforations aligning with the alignment of the indicating characters, and removable plugs for insertion in said perforations so that all but selected perforations may be closed.
- 20 6. A switch lock of the kind indicated comprising a casing, a plurality of concentric disks arranged in said casing in superposed relation and provided at their peripheries with indicating characters, disk actu-

ating means, and a removable back or bottom 25 for the casing, the disk actuating means comprising a shaft and a back or bottom having a flat spring bearing upon the shaft, the back or bottom having an interlocking engagement with the casing.

30 7. A switch lock of the kind indicated comprising a casing, a plurality of concentric disks arranged in said casing in superposed relation and provided at their peripheries with indicating characters, disk 35 actuating means, a removable back or bottom for the casing, the disk actuating means comprising a shaft and a back or bottom having a flat spring bearing upon the shaft, the casing having an inturned peripheral 40 flange provided with uniformly spaced key-hole slots and the bottom having peripheral radial ears insertible through the open sides of said slots, and pins engaged in the lateral extensions of said slots.

In testimony whereof he affixes his signature.

BERKET H. TAYLOR.
